JOHN P. WILLIAMS, OF BAYSIDE, NEW YORK, ASSIGNOR TO DUPLEX ELECTRIC COMPANY, OF NEW YORK, N. Y., A CORPORATION OF DELAWARE

AUTOMATIC SOUND SIGNALING AND REGULATING SYSTEM FOR MICROPHONES USED IN ELECTRIC ALARM SYSTEMS

Application filed September 8, 1927. Serial No. 218,351.

This invention relates to an automatic sound regulating and signaling system for microphones used in electric alarm systems.

Electric burglar-alarm systems as now usually employed for the protection of vaults or other structures comprise a protective circuit concealed within the protected structure and so arranged that an attack thereon will cause actuation of the circuit and send a signal or alarm to a distant station or desired point. An example of such protective systems is indicated in my previous Patent No. 1,436,926, of November 28th, 1922.

It has become the custom to also employ in such protective systems microphone units concealed within the protected structure and so arranged in the protective circuit that an attack involving noise or sound will actuate the microphone and cause operation of the signal or alarm circuit. One example of the supplementary use of microphones in electric protective systems is indicated in my co-pending application for patent, Serial No. 207,538, filed July 21, 1927.

The microphone units usually so employed are of the type which operates on the same general principles as a telephone transmitter, in which any sound will disturb the diaphragm and the vibration of the diaphragm disarranges the normal position of small carbon balls resting against its back, and this disarrangement or stirring-up of the carbon balls modifies resistance of the microphone and correspondingly modifies the current passing therethrough.

The difficulty experienced with such microphone protective systems has been that unnecessary signals or alarms have been caused by operation of the microphones under the action of local vibrations or outside sound conditions (other than an actual attack by hammering, knocking or otherwise upon the protected structure), such as extraneous vibrations or sounds due to passing trolley cars, or trucks, near-by railroad trains, thunder storms, lightning, etc.

It is the object of my present invention to entirely and effectively overcome the disadvantages existing in such microphone protective systems, and to provide an improved

regulating system of this type which will afford full protection against false signals or alarms due to ordinary vibrations or sounds in the vicinity of the protected structure or to any inherent breaking or defect in the microphone unit itself.

To these ends my improved system provides means intermediate of the microphone units and the main signal or alarm which is located at the distant station or desired point at which an alarm is to be given in the event of an attack upon the vault or structure protected by the system, which intermediate means is operative to regulate or "accumulate" sounds from the microphone caused by ordinary extraneous vibrations or sounds other than an actual attack upon the protected structure and signal such vibrations by means of an intermediate alarm or warning signal before a vibration point is reached which will cause actuation of the main station signal or alarm.

In the accompanying drawings I have illustrated diagrammatically the improved system for controlling the action of the microphone units to regulate or "accumulate" the vibrations preliminary to any actuation of the main signal or alarm.

Referring to the drawings, the dotted outline 14 indicates the vault or other protected structure, within which the microphones and regulating and controlling means and circuits thereof are protectively installed. The microphone units, indicated at 15 (I have herein shown two units in series), are in circuit with the protective system of the vault or protected structure, such protective circuit wires or conductors being indicated at 16-17, and a battery or source of electrical energy, 18, and a meter relay of usual construction, 19, are included in the circuit. This circuit is completed through the microphones as follows: From the positive side of the battery 18, through a wire, 20, to and through the coil, 21, of the relay 19, and from the coil through the wire 17 to the microphone 15 and across through a connecting wire, 22, to the other microphone 15 and from thence back through the wire 16 to the negative side of the battery 18. This continuous normally-

closed circuit energizes the coil of the relay 19 and thus maintains the contact needle, 23, of the relay in the normal position as shown.

The sound regulating means is preferably 5 mounted or enclosed within a suitable boxing or casing, as indicated by the dotted outline 24, and the mechanism is herein shown in a normally set position ready for operation. The preferred mechanism comprises a suitable 10 clock spring movement adapted to be key-wound, the gears, indicated at 25, of which control the operation of a hand or pointer, 26, fixed upon a revolute shaft, 27. Back of said pointer is mounted in fixed position 15 a dial, 28, concentrically marked in steps to be indicated by the pointer.

I have herein shown the dial as marked in step points numbered "1" to "19" running 20 clock-wise from a central point 0 at the top (which central point is that at which the main signal or alarm will be actuated), but any other suitable step-marking may be employed. The pointer is manually set as desired with relation to the step points and the 25 number of microphone vibrations to be regulated or "accumulated" to take up ordinary extraneous sounds before the main signal or alarm is actuated. For illustration, I have herein shown the pointer 26 set at the step 30 figure "5," which will afford five vibration steps ("4," "3," "2," "1") in operation before the pointer reaches the main alarm point 0. The step movement of the pointer is the reverse of clock-wise, moving from the higher 35 to the lower step markings on the dial, and is controlled in its operation under the successive sound vibrations by the action of an electro-magnet relay, 29, having its armature, 30, carrying a dogging spring, 31, to the end 40 of which is pivotally mounted a ratchet pawl, 32, engaging one of the clock movement gears 25. the action being such that the operation of the armature 30 causes the ratchet pawl 32 to lock and release the clock 45 movement and thus effect the travel of the pointer 26 over the dial 28 in successive steps one point at a time.

Fixed to the pointer 26 and carried thereby, preferably back of the dial, is a disc, 33, of suitable insulating material, which disc carries two suitably spaced contact points, respectively indicated at 34-35, both of which are grounded, as indicated at 36, to the positive polarity of the main operating 50 battery, shown at 37. In the travel of the pointer these contact points respectively and successively make contact with two spring contact plates, respectively indicated at 38-39, which are in circuit to indicate the 55 travel of the pointer 26 and respectively give a preliminary warning signal or alarm, and a final main signal or alarm.

The arrangement and location of the contact points 34-35 and the contact plates 60 38-39 may be as desired with relation to the

step points on the dial and the travel of the pointer. In the present illustration, the spacing of the contact points 34-35 is such that when the pointer 26 (set at the dial figure "5") moves to the dial figure "4" the 70 spring contact plate 38 makes contact with the contact point 34 and completes a circuit through a warning or preliminary signal which indicates that after four more step movements of the pointer, caused by vibrations or sound waves, it will be at the main alarm point 0 at which a signal or alarm will be sent to the distant alarm station, and when the pointer reaches the alarm point 0 the 75 spring contact plate 39 makes contact with the contact point 35 to complete the main alarm circuit.

It will be understood that the pointer 26 can be initially set at any desired point with relation to the dial scale, according to the 80 number of vibration or sound steps it is desired to "accumulate" before the preliminary warning signal or alarm is given, and that, in the successive step movements thus provided for before the main signal or alarm is 85 actuated, when the pointer reaches the dial figure "4" (in the present illustration of the relative location of the circuit contact points 34-35 and the contact plates 38-39) the preliminary alarm or signal will be actuated. 90 Then, if the step movements have been caused by extraneous or local vibrations or sounds other than an actual attack upon the protected structure, the pointer 26 can be again set 95 back upon the dial scale to the desired point 100 for further regulation of such extraneous vibrations; but, otherwise, if the vibrations or sounds continue or are caused by attack, the further step movements of the pointer will 105 continue until the main alarm point 0 is reached, at which the main signal or alarm (which may be a gong, siren, lamp, or any other audible or visual device) at the main station will be actuated.

In the step-movement travel of the pointer 110 and its disc the circuit of the preliminary warning signal or alarm will be broken as soon as the contact point 34 passes the spring contact plate 38, and the circuit of the main signal or alarm will be set in operation as soon 115 as the contact point 35 reaches the spring contact plate 39.

In operation, when the sound waves, caused by vibrations or an attack upon the protected structure, act upon the diaphragm of the 120 microphones 15, disturbing the position of the carbon balls in circuit and thus changing the total resistance of the microphones, which resistance change is of course due to the volume of the sound wave acting upon the diaphragm, the sudden change in resistance sets up a pulsating current on the before described closed circuit through the coil 21 of the meter relay 19, and this pulsating current causes the contact needle 23 of the relay 130

to deflect and come into contact with the relay contact points, indicated at 40, and a circuit is completed through conductors and means as follows: From the positive side of the 5 operating battery 37 through a wire, 41, to and through the contact needle 23 and contact point 40 and a wire, 42, to the coil, 43, of an automatic-drop relay, indicated at 44, and from thence through a wire, 45, back to 10 the negative side of the battery 37.

The foregoing circuit energizes the coil of the relay 44 and attracts its armature, 46, and the armature makes contact with a contact point, 47, when another circuit is completed through the coil, 48, of the electro-magnet 29 which controls the action of the sound regulating or "accumulating" mechanism, through conductors and means as follows: From the positive side of the operating 15 battery 37, which is grounded, as indicated at 49, to the ground, indicated at 50, of the electro-magnet coil 48, through said coil and a wire, 51, to the contact 47, and through the relay armature 46 and a wire, 52, to the 20 wire 45, and from thence to the negative side 25 of the battery 37.

From the foregoing description it will be noted that three circuits are comprised in the initial operation; first, the initial normally 30 closed protective circuit; second, an intermediate circuit which is actuated by the opening of the protective circuit; and third, a supplementary circuit which is actuated by the intermediate circuit and which in turn 35 controls the operation of the regulating mechanism which governs the signaling or alarm circuits.

When the actuation of the supplementary circuit above described energizes the coil 48 40 of the electro-magnet 29, the armature 30 thereof is attracted and this releases the pawl ratchet 32, through the lifting of the dogging spring plate 31 carried by the armature, and the operation of the clock-spring movement 45 of the regulating mechanism starts.

It will be understood that the foregoing action of the circuits and consequent operation of the clock-spring movement is caused by a single vibration or sound wave action 50 upon the microphones, and that when this single vibration ceases the microphones will resume their normally-closed circuit status through the carbon balls, the circuits before described will resume normal status, 55 and the clock-spring movement will be again locked upon release of the armature 30 of the electro-magnet 29. By this action every single vibration of a given volume or sound 60 causes the pointer 26 to move one step at a time over the dial scale until the points are reached at which the preliminary warning signal or alarm and then the main signal or alarm will be respectively actuated.

The respective signal or alarm circuits, respectively including the spring contact plates

38-39, are completed through conductors and means as follows: When the contact plate 38 comes in contact with the initial contact point 34 on the disc 33 carried by the pointer 26, the warning-signal circuit is completed from the ground 49 of the positive side of the operating battery 37 to the ground 36 of contact point 34, and from thence through said contact point and the contact plate 38 and a wire, 53, to and through the 70 warning signal or alarm, indicated at 54, (which may be a bell or other adapted means) and through a wire 55, back to the negative side of the battery 37. The completion of this warning signal circuit indicates that the 75 pointer 26 is approaching within a few step points of the main alarm point 0 and that in order to avoid the actuation of the main signal or alarm unnecessarily by extraneous vibrations from any cause other than actual 80 attack upon the protected structure the pointer 26 should be moved back a desired number of steps on the scale of the dial, and as soon as this is done the just described 85 warning circuit is of course broken.

But, under conditions of an actual attack upon the protected structure, the consecutive blows or hammering each cause a step movement of the pointer 26, and as the blows continue the warning circuit is first actuated and 90 as the pointer continues its movement the warning circuit is broken and the main signal or alarm circuit is completed, as soon as the 95 alarm point 0 is reached and the contact point 35 is in contact with the contact plate 39, from the ground 49 of the positive side of the battery 37 to the ground 36 of contact point 35, and from thence through said contact point and the contact plate 39 and a wire, 56, to and through the main signal or alarm, 100 indicated at 57, and through a wire, 58, and the wire 55 back to the negative side of the battery 37.

It will thus be noted that there are two 110 separately operating circuits from the regulating means, respectively for the preliminary warning signal or alarm and the main signal or alarm, and that when the preliminary warning signal circuit is in operation the main signal circuit is of course broken and that when the main signal circuit is in 115 operation the preliminary warning signal circuit is broken and there is no possibility of any current passing through the wire 53 and the warning signal 54.

It will also be noted that the before described intermediate circuit which is actuated by the initial protective circuit and which actuates the automatic-drop relay 44, 120 and the supplementary circuit which is actuated by the intermediate circuit and which actuates the electro-magnet 29 which operates to release and lock the regulating means, and also the two respective circuits from the 125 regulating means and which respectively ac-

tuate the warning signal and the main signal, are all operative on the main operating battery or source of electrical energy 37, and that the initial protective circuit operates on 5 its own battery 18.

It is also to be understood that the device 10 operates equally as well with a plurality of continuous alarms of intermittent duration as well as an alarm of continuous duration as the continuous sounds, and effect the microphones the same as a plurality of intermittent alarms. The device will thus operate either on the intermittent sound such as hammering, or on a sustained sound such as a 15 whistle or drilling.

The operation and advantages of my invention will be readily understood. By 20 merely setting the pointer 26 at the desired point on the dial scale any desired number of microphone vibrations can be regulated or "accumulated" before the warning signal or alarm is actuated, and when the warning signal is given the pointer can be again reset if desired, as the number of extraneous 25 vibrations or sounds differs according to the locality of the protected structure, and thus any unnecessary or false alarms by actuation of the main signal or alarm will be conveniently and effectively avoided, but the main 30 signal or alarm will be actuated, in the event of an attack upon the protected structure, as soon the regulated number of vibrations as provided for in the desired setting of the mechanism have been accumulated and the 35 pointer reaches the alarm point 0 in its step movements.

I do not desire to be understood as limiting myself to the detail construction and arrangement of parts as herein shown and described, as it is manifest that variations and 40 modifications therein may be resorted to, in the adaptation of my invention to varying conditions of use, without departing from the spirit and scope of my invention and improvements. I therefore reserve the right to 45 all such variations and modifications as properly fall within the scope of my invention and the terms of the following claims.

Having thus described my invention, I 50 claim and desire to secure by Letters Patent:

1. A microphone protective system of the class described for a structure to be protected, comprising a microphone sound detector located in a position to be actuated during a burglarious attack, a relay in circuit with said microphone, movable means controlled by said relay responsive to both intermittent and continuous vibrations of said sound detector, and an alarm circuit controlled by said means to actuate said alarm only after a predetermined movement of said means.

2. A microphone protective system of the class described for a structure to be protected 55 comprising a microphone sound detector lo-

cated in a position to be actuated during a burglarious attack, a relay in circuit with said microphone, a movable accumulator mechanism, an escapement mechanism controlled by said relay and moving said accumulator mechanism, said escapement mechanism being moved in response to both intermittent and continuous vibrations of said sound detector, and an alarm circuit controlled by said accumulator mechanism to 70 actuate said alarm only after a predetermined movement of said accumulator mechanism, said accumulator mechanism being adapted to be reset a predetermined amount. 75

3. A microphone protective system of the class described for a structure to be protected, comprising a microphone sound detector located in a position to be actuated during a burglarious attack, a relay in circuit with said microphone and operated by 80 the vibrations thereof, an escapement mechanism controlled by said relay responsive to both intermittent and continuous vibrations of said sound detector, an alarm circuit controlled by said escapement mechanism to 85 actuate said alarm after a predetermined movement of said mechanism, a dial and a manually controlled means to reset said escapement mechanism a predetermined amount on said dial to determine the extent 90 of movement thereof before actuation of said alarm.

In testimony whereof I have signed the foregoing specification.

JOHN P. WILLIAMS.
